UNITED STATES PATENT OFFICE.

CONRAD REHBEIN, OF DETROIT, MICHIGAN, ASSIGNOR TO HAYES MANUFACTURING COMPANY, OF DETROIT, MICHIGAN, A CORPORATION OF MICHIGAN.

FLUID-PRESS.

1,207,624.

Specification of Letters Patent.

Patented Dec. 5, 1916.

Application filed April 29, 1916. Serial No. 94,449.

To all whom it may concern:

Be it known that I, CONRAD REHBEIN, a citizen of the United States, residing at Detroit, county of Wayne, State of Michigan, have invented a certain new and useful Improvement in Fluid-Presses, and declare the following to be a full, clear, and exact description of the same, such as will enable others skilled in the art to which it pertains to make and use the same, reference being had to the accompanying drawings, which form a part of this specification.

This invention relates to fluid presses for forming sheet metal, and has for its object a fluid press provided with an automatically opening and closing female die for the purpose of forming with rapidity articles which have an overhang so as to make impossible the successful use of a solid female die.

20 The press is especially designed for forming sheet metal automobile body parts, such as automobile shrouds or cowls.

In the drawings, Figure 1 is a side elevation of the press with the dies closed. Fig. 25 2 is a similar view with the dies opened out, showing the shroud completely formed. Fig. 3 is a section on the line A—A of Fig. 1.

These dies are intended to assist in the 30 forming of sheet metal by the use of fluid pressure, preferably the pressure of water. Inasmuch as the water pressure used is very high—being all the way from 600 to 1,800 lbs. to the square inch—these dies 35 must be very substantially constructed, and in fact, the complete set of dies will weigh anywhere from 10 to 25 tons.

The female die is provided with a shaping concavity *a*. What would ordinarily be 40 called the male die is provided with a water distributing chamber *b* into which leads a passageway *c* connected with a source of water under pressure. *d* designates a gasket set deep into the lower die to prevent its 45 being blown out by the water pressure.

The ram *e* is provided with a center key *f* bolted to its bottom, and this key is provided with heels *g* having their lower inner corners chamfered. The two female die 50 parts are slotted at their tops to fit over the key so as to be restrained from lateral movement in their oscillatory motions in opening and closing. Each die part is provided with a pair of trunnions *h* which 55 loosely play in the squared aperture formed

by the *U* bracket *i* bolted to the bottom of the ram. There are four *U* brackets for the four trunnions. To the ends of the bolster *s* is bolted a pair of obliquely disposed rails *t*. These rails serve to guide or force the lower 60 ends of the two-part female die in toward the male die when the die is closed together. The depending heels *g* of the key *f* secured to the ram engage behind the chamfered shoulders *j* when the two die parts are closed 65 together and serve to resist the tendency of the die parts to spread at the top under the heavy water pressure. The adjacent faces of the female die parts are obliquely cut away at the top so that in closing and 70 opening the die parts can tip toward each other to allow the heels *g* to clear the shoulders.

Thrust blocks *x* are made integral bosses on the male die casting and project over the 75 female die parts when closed in. These thrust blocks are provided with bolts *y* which project through and have large nuts *z* on their threaded ends so that shims *w* can be pinched in between the large plate-like nuts and the block to take up any play between the thrust blocks and female die parts. These thrust blocks are required on only one side as the taper of the male and 80 female die parts prevents separation in the opposite directions.

It will be noted that the cowl or shroud is widest at the top and hence could not be pulled out of a solid female die without distorting it.

90 What I claim is:

1. In a press, the combination of a bolster, a ram, a male die provided with a water distributing chamber, and a two-part female die arranged to automatically open and close 95 as the ram and bolster are separated and brought together.

2. In a press, the combination of a ram, a bolster, a male die provided with a water distributing chamber and attached to the bolster, a female die having two parts tending to separate and each of which is hung on the ram and provided with a shaping concavity, and means for guiding the two female die parts into closed position when the ram approaches the bolster and the die 100 is closed together.

3. In a press, the combination of a ram, a pair of female die parts tending to part and provided with shaping concavities and 110

loosely pivoted to the ram, a bolster, a male die part provided with a chamber to hold a pressure conveying element, and guiding means for automatically causing the female die parts to close about the male die as the ram approaches the bolster.

4. In a fluid press, the combination of a ram provided with U-like brackets, a pair of female die parts each provided with a shaping concavity, a pair of trunnions loosely pivoted in the said U-like brackets, a bolster, a male die secured to the bolster and provided with a water distributing chamber, and guiding means for throwing the female die parts inwardly toward the male die as the ram and bolster come toward each other.

5. In a fluid press, the combination of a ram, a pair of female die parts pivoted to the ram and normally tending to swing apart, a bolster, a male die secured thereto and provided with a water distributing chamber, and guiding means on the bolster for throwing the female die parts in toward the male die upon the approach of the ram to the bolster.

6. In a fluid press, the combination of a ram, a key attached thereto, a pair of female die parts provided with shaping concavities and each provided with a slot so that the die parts may straddle the said key, means for pivoting the upper ends of the female die parts to the ram, a bolster, a male die secured to the bolster and provided with a water distributing chamber, and means for guiding the lower ends of the female die parts in against the male die upon the descent of the ram.

7. In a fluid press, the combination of a ram, a key bolted to the bottom of the ram and provided with heels, a pair of female die parts pivoted to the ram and provided with slots in their tops for straddling the rail and having recesses at the ends of the slots to form shoulders against which the heels of the said key may abut to resist the

spread of the dies under pressure, a bolster, a male die secured thereto and provided with a water distributing chamber, and means for guiding the lower ends of the female die parts in toward the male die when the ram descends.

8. In a fluid press, the combination of a ram, a pair of female die parts hung to the ram and tending normally to swing apart, a bolster provided with a pair of inclined rails, a male die secured to the bolster and provided with a water distributing chamber, whereby when the ram descends the lower ends of the female die will strike the inclined rails and be guided against the male die, substantially as described.

9. In a fluid press, the combination of a ram, a female die hung to the ram, a bolster, a male die secured to the bolster and provided with a water distributing chamber, and thrust blocks on the dies to overlap adjacent die parts to avoid side thrust.

10. In a fluid press, the combination of a ram, a female die secured to the ram, a bolster, a male die secured to the bolster and provided with a water distributing chamber, thrust blocks on the dies to overlap adjacent die parts, and shims securable on the thrust blocks to take up looseness.

11. In a fluid press, the combination of a ram, a key secured thereto and provided with heels, a pair of female die parts pivoted to the ram and having the upper parts of their adjacent faces obliquely cut away and having slots in the tops of the die parts so they can straddle the key and recesses at the ends of the slots to afford shoulders against which the heels abut when the die parts are closed together, a bolster, a male die and means for guiding and restraining the female die parts to close upon the male die.

In testimony whereof I sign this specification.

CONRAD REHBEIN.
